UNITED STATES PATENT OFFICE.

STEFAN HRDINA, OF PRACHEN-SELTY, CZECHOSLOVAKIA.

ATOMIZER OR SPRAY NOZZLE.

Application filed December 16, 1925. Serial No. 75,809.

To all whom it may concern:

Be it known that I, STEFAN HRDINA, a Czechoslovakian citizen, residing at No. 3 of Prachen-Seltyn, Czechoslovakia, have invented a certain new and useful Atomizer or Spray Nozzle, of which the following is a specification.

This invention relates to atomizers or spraying nozzles, and more particularly nozzles of the type comprising a blast jet for inducing flow of liquid which is atomized by the blast and delivered from the nozzle in an atomized condition.

One object of this invention is to provide a jet pipe of the type in question with means for centering it in the nozzle.

A further object is to provide such jet pipe with ribs which are formed by pressing and folding the metal of the pipe, whereby integral ribs of two thicknesses of metal pressed closely together are produced.

Yet another object is to provide a jet pipe of the type in question with external ribs and a reduced bore at its delivery end, said ribs constituting means for centering the pipe in the nozzle and also, if desired, whirling means for the liquid, and said reduced bore constituting a cone or jet nozzle for the concentrated delivery of the air.

In the annexed drawing forming part of this specification, one construction embodying this invention is illustrated by way of example, and in this drawing:

Figure 1 is partly a central vertical section and partly a side elevation of a nozzle device comprising a jet pipe having centering ribs.

Figure 2 is an elevation on a larger scale of the delivery end of the jet pipe, and

Figure 3 is a plan of Figure 2 as seen from below.

Referring to Figure 1, 1 is a spigot or fitting for supporting the atomizer nozzle 3 which is screwed into such fitting. The said nozzle 3 is in communication with a bore in the fitting, which bore, in turn, is in communication with a suction or supply pipe 4 conveying to the nozzle the fluid to be atomized.

Into the upper part of the fitting, and in axial alignment with the nozzle 3, there is screwed a nipple 2 carrying a jet pipe 5 which latter is to be centered within the nozzle 3. The nipple 2 is adapted to be connected with a hose or other duct supplying the blast or fluid under pressure.

Referring to Figures 1 to 3, it will be seen that the delivery end of the jet pipe 5 is deformed so as to produce externally thereof radial ribs 6 and so as to reduce the outlet end of the bore thereof to the cone form illustrated.

This shaping can be effected by inserting a mandril into the jet pipe and using a press tool which contracts the jet pipe onto the mandril, while at the same time folding and pressing the metal to produce the ribs 6, each of which, as seen in Figure 3, is composed of two thicknesses of metal pressed tightly together.

The ribs 6 extend sufficiently beyond the circumference of the jet pipe 5 to serve as centering means within the nozzle 3. Thus, when the jet pipe 5 is inserted into the nozzle 3 from the upper end thereof in Figure 1, and the nipple 2 is screwed down in the fitting 1, the points at the greatest width of the ribs 6 engage and move down the interior of the nozzle 3 and thus accurately center the jet pipe 5.

It will be noted that the jet pipe 6 is inserted so that its orifice lies within the orifice of the nozzle 5, and in this way a chamber 7 is formed.

Upon supplying compressed air or pressure fluid to the nipple 2, such air or fluid passes down the jet pipe 5 and issues from the coned or constricted jet orifice as a truly central jet owing to the accurate centering due to the ribs or fins 6. This jet induces liquid to flow through the pipe 4 and the bore of the fitting 1 into the upper part of the fitting and down the annular passage between the jet pipe 5 and the nozzle 3. Such liquid is disturbed in passing the fins or ribs 6 and entering the chamber 7, and may be caused actually to swirl in the chamber 7. Thus, the liquid, on being impinged upon and taken up by the jet from the pipe 5, is completely atomized and is delivered in such atomized condition from the orifice of the nozzle 3.

I claim:

1. An atomizer or spraying nozzle, comprising a nozzle tube, and a concentric pressure jet tube in the bore thereof; the jet tube having its outlet end deformed to constrict the same and to produce integral centering members which are slidably engaged with the wall of the bore of the nozzle tube.

2. An atomizer or spraying nozzle, comprising a nozzle tube, and a concentric pres-

2
sure jet tube in the bore thereof; the jet tube having its outlet end deformed to constrict the same and to produce integral radial centering fins which are slidably engaged with the wall of the bore of the nozzle tube.

3. An atomizer or spraying nozzle, comprising a nozzle tube, and a concentric pressure jet tube in the bore thereof; the jet tube having its outlet end deformed to con-

strict the same and to produce integral radial centering fins composed of two thicknesses of metal folded closely together, said fins being slidably engaged with the wall of the bore of the nozzle tube.

In testimony whereof I have signed my name to this specification.

STEFAN HRDINA.
